UNITED STATES PATENT OFFICE.

HENRY T. GERDES, OF LEBANON, PENNSYLVANIA, AND WALTER C. ELZE, OF WOODHAVEN, NEW YORK, ASSIGNORS TO HAUCK MANUFACTURING COMPANY, OF BROOKLYN, NEW YORK, A CORPORATION OF NEW YORK.

PORTABLE LOW-PRESSURE OIL-BURNING FORGE.

Application filed November 19, 1924. Serial No. 750,822.

The invention relates to a portable forge or furnace unit, especially suitable for the heating of rivets and other metal objects; and it has for its object to so design an apparatus of this character that the same will be self-contained and readily operated, even under conditions where other types would not be suitable, and require no particular skill or intelligence on the part of an operator. The novel unit is designed to carry a blower or like apparatus for affording air under pressure, eliminating thereby the usual and necessary considerable lengths of piping or hose.

15 A further object of the invention is to render unnecessary any adjustments after the device has once been set for operation. A still further object of the invention consists in the novel arrangement of the various parts whereby the apparatus complies with safety and insurance requirements, a relatively low pressure being maintained on the liquid fuel, as oil, employed; and the said pressure, furthermore, prevailing only 25 during the operation of the forge.

A still further and most important feature of the invention consists in the novel arrangement whereby the air pressure is built up gradually, the burner receiving air 30 prior to oil, and the reverse taking place upon shutting down of the apparatus. This arrangement promotes safety of operation in that oil in bulk is prevented from being ejected from the burner nozzle.

35 A still further object consists in the novel arrangement whereby the particular position of the forge is substantially without effect in checking the flow of air thru the burner air line or of sealing such burner air 40 line by oil; and, furthermore, whereby, should oil for any reason find its way in proximity to such lines, it may be caused to drain back into this supply tank under the action of gravity. The invention has for its 45 object also the limiting of the oil level in the filling of the supply tank.

A still further object of the invention resides in the localizing of all controls at one point, that is to say, substantially eliminating the human element, it being required 50 merely to close an electric circuit to a low-powered electric motor, running on for ex-

ample an ordinary 110 or 220 volt circuit, for effecting the operation of the forge. This arrangement admits of the ready provision of a safety switch directly on the apparatus or its frame-work in conformity with the underwriters' requirements.

The novel tank construction for retaining the liquid fuel as oil admits, also, of the continuous passage of comparatively cool air over said oil so that its temperature is maintained relatively low at all times—approximately that of the surrounding atmosphere. This further reduces the fire hazard in 65 eliminating preheating of said oil, which is quite unnecessary if the proper mixture of air and oil is set once for all to afford perfect combustion. The apparatus thereafter requires no further adjustments or setting 70 of valves as the combustible mixture quickly builds up upon completion of an electric circuit to operate devices which control both the air and fuel supply, the air supply serving not only to atomize the liquid fuel employed but, preferably, also to effect its delivery from the tank which contains the 75 same. The particular arrangement of air and fuel supply set forth admits also of minimizing the effect of pulsations in the air 80 supply apparatus by affording a storage space for this air separate and distinct from said oil.

A still further object of the invention resides in the particular combination of the 85 fuel supply and the control for the air supply whereby the mixture issuing from the burner for combustion may be made relatively lean or rich by a single adjustment.

The nature of the invention, however, 90 will best be understood when described in connection with the accompanying drawings, in which—

Fig. 1 is a side elevation of the forge unit; and Fig. 2 is a front elevation thereof.

Fig. 3 is a detail vertical section thru the oil supply tank; and Fig. 4 is a transverse section taken on the line 4—4, Fig. 3, looking in the direction of the arrows.

Referring to the drawings, 10 designates 100 a suitable frame for supporting the forge or furnace which may be carried as a whole, for example, upon a pair of wheels 11 to permit of the units being conveniently moved about,

as by drawing on the handle 14 attached to the forward end of the frame. The various members comprising the movable portable unit are arranged within the frame structure 10 in manner to best economize space, but with the heating chamber 15 at the uppermost part thereof. This portion of the apparatus is of any well-known or standard type of heater provided with, for example, a lateral opening 16 for introducing and removing the rivets or other metal objects which it is desired to heat. A shelf 17 as well as a rivet pan 18 located below the same are also preferably associated with said heater portion of the apparatus. At the forward end of the furnace is arranged a combustion box 19 with which is associated the burner 20 directing therein the combustible mixture for heating the heater 15 to the desired temperature. This burner 20 may be of any well-known type; and is preferably of the type, shown in U. S. Patent No. 1,485,731, in which means are provided for controlling the air orifice of the burner. In the burner 20 illustrated, however, this control is effected thru the rotation of an annular member 21 about the forward end of the burner moving its adjustable tip 22. Below the heater 15 is located the fuel tank 25 which is adapted to contain an ample supply of liquid fuel such as kerosene or heavier oil suitable for providing the desired temperature in the heater or furnace proper 15. Connection is made from the fuel tank to the burner 20 thru a pipe 26 for supplying the oil thereto and also thru a pipe 27 for providing the necessary air for the combustion as well as for the atomization of the liquid fuel. As will hereinafter be set forth, the air is also caused to deliver the oil from the tank 25 to the burner 20.

The air is obtained initially from a blower 28 or similar apparatus for affording air under pressure, said blower being mounted, together with an electric motor 29, on a suitable shelf 30 located beneath the tank 25, the said blower being directly connected to the motor 29 by means of a shaft 29'. This motor serves, thus, to operate the blower, electric energy being provided for this purpose thru a suitable switch device as the plug and socket connection 31, the socket being connected thru a cable 32 with the motor 29 and the plug thru a cable 33 with an exterior source of power (not shown). This arrangement at the same time provides a safety switch upon the apparatus and at which the circuit may quickly be opened, thus conforming with underwriters' requirements. As will hereinafter be more fully set forth, the entire operation of the furnace is dependent upon the connection being established at the plug and socket 31.

It is believed the operation of the blower

28 and connected motor 29 will be apparent without further explanation.

In order to insure the proper operation of the burner and supply of fuel thereto under all conditions and with the greatest simplicity of operation, the tank 25 is specially constructed and the location of the various inlets and outlets respectively to and from the same bear an important relation not only to the tank but also to one another. Referring more particularly to Figs. 3 and 4 of the drawings, it will be noted that the tank 25 is provided with suitable means to prevent flooding of the air supply line, for example thru the interposing of an inclined 80 longitudinally extending partition or baffle 35 near the upper portion of said tank. This partition extends clear across the tank from side to side and is fitted to one end thereof. At the opposite end it terminates 85 at a vertically disposed wall or transverse partition 36 which extends from the top of the tank entirely across same and downwardly to a short distance from the bottom and forms with the corresponding end wall a 90 filling compartment 37. Into this compartment extends, thru the top of the tank, a filling tube 38 which is provided exteriorly of the tank with a suitable cap 39. This filling tube, moreover, is fitted to the tank 95 such that its outer end will be below the lower end of the partition 36 thus preventing the filling of the tank beyond a predetermined level, as indicated.

Liquid fuel admitted into the compartment 37 thru the filling tube 38 extending therein will flow into the main body of the tank 25 thru the space 45 afforded between the lower edge of the wall 36 and the bottom of said tank. In view of the position of the level determining means hereinbefore set forth, it will not be possible to fill this tank to a height exceeding the lower end of the inclined wall 35 and the level is preferably somewhat below same, as indicated. The 110 liquid fuel is taken from the bottom of the tank thru the outlet tube 26 which passes into the said tank and has an opening 46 at its innermost end, said end being located a slight distance above the bottom of the tank. In order to force the liquid fuel thru this tube 26, it is preferred to employ air under pressure which is arranged to be supplied thereto, as thru the air supply pipe 47 whose one end is connected to the blower 28 and 120 whose other end extends into the compartment 48 formed between the upper wall of the tank and the partition 35, the said pipe 47 passing also thru the lower portion of the tank and having its inner end extending an 125 appreciable distance above the partition 35. A series of openings 50 are provided in the wall 36 both above and below the partition 35 to permit the air from the compartment 48 to enter the compartment 37 and to the 130

- liquid fuel in the tank 25 to expel same therefrom. The air from the compartment 48, furthermore, is supplied thru the pipe 27, connected at the top of the tank, to the 5 burner and serves not only to atomize the fuel supplied to the burner thru the pipe 26 but thereby also to lift the same thereto thru the suction effect produced in the burner.
- 10 By the particular construction of tank hereinbefore described, it will be appreciated that the partition 35 will serve as a baffle or splash plate to prevent liquid fuel from accumulating in the upper portion or 15 compartment 48 of the tank notwithstanding various positions which the apparatus may assume in use and which liquid fuel might otherwise seal off the air connections. Moreover, the compartment 48 serves also to 20 minimize the effect of any pulsations in the supply of the air from the blower 28. Furthermore, should any liquid fuel by chance reach the compartment 48, the inclined position of the partition 35 will assist in draining 25 the same, thru openings 51 at the lower end of the partition, away from the openings of the pipes 47 or 27, the latter being shown as located at the extreme forward end of the compartment.
- 30 In operation, the apparatus is started merely by the closing of the circuit at the plug and socket connection 31, constituting also a safety switch, and which starts up the motor 29 and also thereby the blower 28. 35 The air pressure gradually increasing as the motor speeds up, air will be forced to the burner 20 followed by liquid fuel from the tank 25; and thus there is provided a mixture which is gradually built up to the full 40 volume, the reverse taking place upon shutting down of the apparatus so that at no time will be possible for liquid fuel in bulk to be supplied to the furnace. Moreover, in utilizing with the said arrangement 45 of a common means of insuring the fuel and air supply, a burner of the type hereinbefore noted and whereby a control of the air orifice at burner is possible, the novel combination admits of a convenient and simple adjustment for varying the character of the mixture. That is to say, if the annular member 50 be turned in one direction the air orifice of the burner is contracted and if turned in the reverse direction its area is increased. 55 In the former case, the volume of air passing thru the orifice decreases; and by so doing, builds up air pressure in the tank 25 to cause oil to pass out in greater volume and thus enrich the mixture. On the other hand, 60 by increasing the volume of air passing thru the burner orifice, a reduction in pressure in the tank results so that less oil will be delivered and the mixture consequently becomes leaner.
- 65 We claim:—
1. A portable forge comprising a furnace, a burner associated therewith adapted to project a flame into the interior thereof, a liquid fuel supply tank connected with the burner, an inclined partition therein extending from one end of the tank toward the other to provide an air pocket between said partition and the wall of the tank, an air pipe opening into said pocket, an outlet connection from said air pocket to the burner, a 70 blower, an electric motor for driving same, a frame for supporting the aforesaid furnace, tank and motor-driven blower, connections between the said blower and the said tank air pipe, and means to control the operation of said motor. 75
2. A portable forge comprising a furnace, a burner associated therewith adapted to project a flame into the interior thereof, a liquid fuel supply tank connected with the burner, an inclined partition therein, provided with an outlet opening, and extending from one end of the tank toward the other to provide an air pocket between said partition and the wall of the tank, an air pipe opening into said pocket, an outlet connection from said air pocket to the burner, a 80 blower, an electric motor for driving same, a frame for supporting the aforesaid furnace, tank and motor-driven blower, connections between the said blower and the said tank air pipe, and means to control the operation of said motor. 85
3. A portable forge comprising a furnace, a burner associated therewith adapted to project a flame into the interior thereof, a liquid fuel supply tank connected with the burner, an inclined partition therein, provided with an outlet opening, and extending from one end of the tank toward the other to 90 provide an air pocket between said partition and the wall of the tank, an air pipe opening into said pocket thru said partition, an outlet connection from said air pocket to the burner, an oil outlet from the bottom of the tank to the burner, means to limit the liquid fuel level when charging the tank, a blower, an electric motor for driving same, a frame for supporting the aforesaid furnace, tank and motor-driven blower, connections between said blower and the said tank air pipe, and means to control the operation of said motor. 95
4. A portable forge comprising a furnace, a burner associated therewith adapted to project a flame into the interior thereof, a liquid fuel supply tank, an inclined partition therein, provided with an outlet opening, and extending from one end of the tank toward the other to 100 provide an air pocket between said partition and the wall of the tank, an air pipe opening into said pocket thru said partition, an outlet connection from said air pocket to the burner, an oil outlet from the bottom of the tank to the burner, means to limit the liquid fuel level when charging the tank, a blower, an electric motor for driving same, a frame for supporting the aforesaid furnace, tank and motor-driven blower, connections between said blower and the said tank air pipe, and means to control the operation of said motor. 105
- 110
- 115
- 120
- 125
- 130

the burner, a filling tube extending into the tank and having its inlet opening at a level below the lower end of the said inclined partition, a blower, an electric motor for driving same, a frame for supporting the aforesaid furnace, tank and motor-driven blower, connections between the said blower and the said tank air pipe, and means to control the operation of said motor.

Signed at Brooklyn in the county of 10
Kings and State of New York this 11th day
of November, A. D. 1924.

HENRY T. GERDES.
WALTER C. ELZE.
